UNITED STATES PATENT OFFICE.

JAMES H. WARREN, OF SALTILLO, MISSISSIPPI.

BOAT CONSTRUCTION.

1,181,048.

Specification of Letters Patent. Patented Apr. 25, 1916.

Application filed April 6, 1915. Serial No. 19,601.

To all whom it may concern:

Be it known that I, JAMES H. WARREN, a citizen of the United States, residing at Saltillo, in the county of Lee and State of Mississippi, have invented certain new and useful Improvements in Boat Construction; and I do hereby declare the following to be a full, clear, and exact description of the invention, such as will enable others skilled 10 in the art to which it appertains to make and the same.

The general object of this invention is to prevent any water which may enter through the bottom of a row boat, motor boat or similar craft from coming in contact with the occupants of the boat; also to increase the buoyancy of the boat and prevent accidental upsetting of the boat; and to this end the invention consists in providing a boat with a 15 filler formed of layers of cork and of wood and arranged alternately one above the other, within the bottom of the boat, and so arranged that the uppermost layer of the filler will be one of wood so as to provide a floor 20 for the boat.

With the above and other objects in view as will more fully appear from that embodiment of my invention of which the following is a specification, reference being had 25 to the accompanying drawings forming a part thereof in which:

Figure 1 is a side elevation of a boat having a portion thereof broken away so as to show the filler therein. Fig. 2 is a cross 30 section taken on the line 2—2 of Fig. 1.

Referring more particularly to the drawings, the numeral 1 designates a boat of ordinary construction having a bottom 2, sides 3 and keel 4. Located within the boat, 35 is a filler designated as an entirety by the numeral 5 and which is formed of a plurality of layers of wood and cork arranged one above the other, the layers of wood being designated by the letters *a*, *b*, *c*, and *d* and 40 the layers of cork being designated by the letters *e*, *f* and *g*. Each layer of wood is formed of a series of strips 6, as shown in Fig. 2, and the strips forming the layers *a* and *c* are extended transversely of the boat 45 and have the opposite ends secured in any

suitable manner to the sides of the boat, and the strips forming the layers *b* and *d* are extended longitudinally of the boat and at right angles to the strips forming the layers *a* and *c* and are secured in place in 55 any suitable manner. The upper layer *d* is adapted to serve as the floor of the boat, and may be coated with shellac or any suitable material. Each layer of cork may be formed of a continuous sheet or may be 60 formed of pulverized cork, packed tightly between the adjacent layers of wood.

By virtue of arranging the strips forming the layers *b* and *d* at right angles to those forming the layers *a* and *c*, the filler is rendered more compact and the cork layers are held in tight engagement with the adjacent strips forming the layers of wood, thereby resulting in the positive sealing of the 65 crevices between adjacent strips of each 70 layer of wood and preventing any water that may enter through the bottom of the boat, from finding its way through the floor of the boat.

Another advantage derived from the employment of the filler above described, is that the bottom of the boat will be sufficiently weighted so that accidental upsetting of the boat will be entirely prevented.

From the above it will be seen that by 75 employment of a filler, as above described, the boat will be rendered more water proof and its stability increased.

Having thus described my invention, what I claim as new is:

The combination with a boat, of a plurality of superposed layers of wood located within the boat and each formed of sectional strips, the strips forming alternate layers being arranged transversely of the boat and 80 the strips forming the other layers extending longitudinally of the boat, and layers of cork inserted between the layers of wood.

In testimony whereof I affix my signature in presence of two witnesses.

JAMES H. WARREN.
